UNITED STATES PATENT OFFICE.

WILLIAM SARGENT, OF MAHWAH, NEW JERSEY, ASSIGNEE TO THE AMERICAN BRAKE SHOE AND FOUNDRY COMPANY, OF WILMINGTON, DELAWARE, A CORPORATION OF DELAWARE.

Brake-Shoe.

1,328,538.

Specification of Letters Patent. Patented Jan. 20, 1919.

Application filed July 2, 1919. Serial No. 808,307.

To all whom it may concern:

Be it known that I, FIZZ WILLIAM SARGENT, a citizen of the United States, and a resident of Mahwah, in the county of Bergen and State of New Jersey, have made and invented certain new and useful Improvements in Brake-Shoes, of which the following is a specification.

My invention relates to new and useful improvements in railway brake shoes, and particularly to that type wherein the body portion is strengthened and reinforced throughout by casting it around a wrought or mild steel back, the latter being outwardly looped at its central portion to form an integral lug for the attachment of the brake shoe to a brake head.

The outward looping of the reinforcing back at its center to form the attaching lug, in the usual type of brake shoe, provides a weak juncture between the cast metal of the body of the shoe and the reinforcing back adjacent the sides of the attaching lug, so that there is a tendency for the back to become separated from the cast metal of the body of the shoe at these points. Further, that portion of the body of the brake shoe which lies directly beneath the looped lug is unreinforced and should the shoe become fractured adjacent the sides of the lug, that portion of the shoe which lies therebetween may fall away and the shoe in turn spread or open up.

It is accordingly an object of my invention to provide a shoe of the character above described wherein the reinforcing back is prevented from being torn away from the cast metal of the body of the shoe adjacent the sides of the lug, and that portion of the cast body of the shoe which lies directly beneath the outwardly looped lug is reinforced and strengthened.

A further object is to accomplish the aforementioned ends in a simple and novel manner and at the same time strengthen and reinforce the upstanding cast portions of the lug, which in certain types of brake shoes cooperate with the looped portion of the back whereby the attaching lug for securing the shoe to the brake head is formed, the ends enumerated being accomplished without materially adding to the cost of the shoe.

With the above and other objects in view, my invention consists in the improved brake

shoe illustrated in the accompanying drawing and hereinafter described and claimed, and in such variations and modifications thereof as will be obvious to those skilled in the art to which my invention relates.

In the drawing accompanying and forming a part of this application and wherein the preferred embodiment of my invention is illustrated:

Fig. 1 is a view in perspective of a brake shoe embodying the characteristic features of my invention;

Fig. 2 is a view in side elevation thereof, portions being represented in section;

Fig. 3 is a view in vertical section taken on the line 3—3 of Fig. 2;

Fig. 4 is a top plan view of a somewhat modified form of brake shoe, the reinforcing strip and looped lug of the back being further strengthened and reinforced by the presence of upstanding integral lugs;

Fig. 5 is a view in side elevation and partially in section of the foregoing; and

Fig. 6 is a view in vertical section taken on the line 5—5 of Fig. 4.

Referring to the drawing, the reinforcing back 10 is outwardly looped at its central portion to form the integral upstanding lug 11, the same being provided with the usual keyway openings 12 therein. The body 13 of the brake shoe is formed of metal cast about the reinforcing back 10, the two being thus inseparably connected and joined together.

The outward looping of the reinforcing back at its center to form the lug 11 would leave that portion of the shoe which is directly therebeneath unreinforced, and in order to strengthen this portion of the shoe and prevent it from falling away or becoming detached from the main portion of the body of the shoe should the latter become fractured adjacent the sides of the lug, I provide a transverse lug-reinforcing strip 14, the same being composed of a top 15 which projects across the top of the lug 11 and has side walls 16 and toes or anchoring ends 17, the latter being embedded within the cast metal of the body of the shoe and accordingly firmly anchored thereto.

The lug reinforcing strips 14 accordingly prevent any direct strain from being brought to bear upon the reinforcing back adjacent the sides of the looped lug which would tend to tear the back away from the cast metal 11.

of the body of the shoe at these points, these strains being taken up and borne by the transverse lug-reinforcing strip. Further, the toes 17, projecting downward within the body of the shoe, reinforce the cast metal at these points, so that the cast metal of the body of the shoe is reinforced throughout its entire length.

In the modified form of brake shoe shown in Figs. 4, 5 and 6 of the drawing, the reinforcing back 20 is somewhat reduced in width at its center and is outwardly looped at this portion so as to form the integral lug 19 through which extend the usual keyway openings 21. The reduction in width of the reinforcing back at the center provides sufficient space for the formation of the upstanding cast lugs 18, the same coöperating with but projecting above the top of the looped lug 19 of the reinforcing back. Firmly anchored within the cast lugs 18 is the transverse lug reinforcing strip 22, the same projecting across the top of the integral looped lug 19 of the reinforcing back and extending down through the cast lugs 18 so as to reinforce the same, and terminating in the toes 23 which are embedded and anchored within the cast metal of the body of the shoe. Thus the upstanding cast lugs are reinforced and prevented from becoming broken in handling. The looped lug of the back is strengthened and prevented from becoming torn away from the cast metal of the body of the shoe, and the central portion of the shoe, which lies directly beneath the looped lug, is reinforced by the presence of the toes of the wrought or 114 steel lug-reinforcing strip 22.

What I claim is:

1. A brake shoe comprising a body, a reinforcing back with a looped lug embedded

therein, and a lug-reinforcing strip embedded in the body metal of the shoe and projecting across the top of the looped lug of the back.

4.

2. A brake shoe comprising a cast metal body, a reinforcing back embedded therein and provided with an outwardly looped integral lug, and a transverse lug-reinforcing strip with the ends thereof embedded in the body metal of the shoe and the central portion projecting across the top of the looped lug of the back.

50

3. A brake shoe comprising a reinforcing back with an integral looped lug, a body portion cast to said back and reinforced thereby, the body metal projecting upwardly at the sides of the looped lug, and a reinforcing strip embedded therein and projecting across the top of the looped lug of the back.

55

4. A brake shoe comprising a reinforcing back reduced in width at its central portion and outwardly looped to form an integral lug, a body formed of metal cast about said reinforcing back with portions thereof projecting upwardly at the reduced portion of the reinforcing back and forming integral cast lugs adjacent the looped lug of the back, and a transverse lug-reinforcing strip embedded in the cast metal of the lugs of the body and projecting across the top of the looped lug of the back.

60

Signed at New York, borough of Manhattan, in the county of New York and State of New York, this 2d day of July, A. D., 1919.

FITZ WILLIAM SARGENT.
